CLAIM

The ornamental design for a tire, as shown and described.

DESCRIPTION

FIG. 1 is a perspective view of my new design, it being understood that the tread pattern is repeated throughout the circumference of the tire, the opposite side being substantially a mirror image thereof;

FIG. 2 is a front elevational view thereof;

FIG. 3 is a side elevational view; and,

FIG. 4 is an enlarged fragmentary front elevational view taken from FIG. 2.
